Primary Examiner — Cathron C Brooks*Assistant Examiner* — Sharon S Oum(74) *Attorney, Agent, or Firm* — Knobbe Martens Olson & Bear LLP(57) **CLAIM**

The ornamental design for an air moving device, as shown and described.

DESCRIPTION

FIG. 1 is a front, left, and top side perspective view of an air moving device embodying our new design;

FIG. 2 is a front, bottom, and right side perspective view thereof;

FIG. 3 is an expanded front, bottom, and right side perspective view of a portion of the bottom thereof;

FIG. 4 front side elevational view thereof;

FIG. 5 is a back side elevational view thereof;

FIG. 6 is a top plan view thereof; and

FIG. 7 is a bottom plan view thereof; and,

FIG. 8 is an expanded bottom plan view of a portion of the bottom thereof.

Broken lines are used to illustrate features of the air moving device which form no part of the claimed design. Dot-dash lines are used to illustrate boundary lines and form no part of the claimed design.

1 Claim, 8 Drawing Sheets# US D820,967 S
